UNITED STATES PATENT OFFICE

152,350

DESIGN FOR A COIL WINDING MACHINE

Harry W. Moore, Dayton, Ohio

Application December 29, 1945, Serial No. 125,164

Term of patent 14 years

(Cl. D54—6)

To all whom it may concern:

Be it known that I, Harry W. Moore, a citizen of the United States, residing at Dayton, in the county of Montgomery and State of Ohio, have invented a new, original, and ornamental Design for a Coil Winding Machine, of which the following is a specification, reference being had to the accompanying drawing, forming a part thereof:

In the drawings, Figure 1 is a perspective view of a coil winding machine, showing my new design.

Figure 2 is a front elevational view of the coil winding machine, shown in Figure 1.

Figure 3 is a rear elevational view thereof.

Figure 4 is a fragmentary end view, as viewed from the left of Figure 2.

Figure 5 is a fragmentary end view, as viewed from the right of Figure 2.

I claim:

The ornamental design for a coil winding machine, as shown.

HARRY W. MOORE.
